UNITED STATES PATENT OFFICE

FRANZ MELCHER AND ERNST SCHNEIDER, OF VIENNA, AUSTRIA

BLADE OF SCREW PROPELLERS

Application filed June 23, 1930, Serial No. 463,319, and in Austria May 28, 1929.

This invention relates to a new and improved design for the blades of screw-propellers of every kind operating in any medium, and has for its object to achieve the greatest possible efficiency and load capacity of the propeller in which it is incorporated. The invention consists essentially in a particular plotting of the generating guide line of the twisted blade surface by means of which the holding capacity of the blades of the propeller is increased while cavitation at the boss is at the same time checked. The generating guide line above and hereinafter mentioned is the intersecting line of a plane drawn through the propeller axis and the outer most blade point with the surface of the blade.

One known expedient for the increasing of the holding capacity of propeller blades and for the recovery of the energy of flow consists in the employment of nozzle- or suction-pipe-shaped jacketing of the blade shells of turbines or of enclosed propellers. In practise, however, this method has been abandoned, since the gain in thrust obtained by the use of the nozzle is more than outweighed by skin-friction and tow-resistance.

A great variety of further expedients have been tried for the purpose of improving propellers, mostly relating to the pitch, outline, radial or peripheral curvature, or to the inclination of the propeller blades towards or away from the direction of travel. The attempt has also been made to increase the efficiency of propellers by designing blades of unusual thinness; but these again have proved to be disadvantageous in consequence of comparatively slight draught and the development of cavitation at heavier loads. All these and similar attempts hitherto made with the object of improving upon the normal designs of propeller blades have led to no advance of general value, the advantage gained in any particular direction in any one case being outweighed by disadvantages in other directions.

The tests and calculations upon which the present invention is based have proved that the plotting and shaping of the generating lines of the blade offers the possibility of

improving upon even the most perfect propeller of given characteristic. This conclusion is derived from the following basic facts and considerations.

Tests with a water propeller have proved that a backward curve of the generating lines away from the direction of travel reduces the thrust of the propeller, since the convergence of the tail-water is thereby promoted, while the fluid pressure at the boss is increased and the danger of cavitation in this region reduced. This expedient therefore leads to a reduction in the holding capacity and thus also in the thrust of the propeller. The provision of a tubular suction nozzle enclosing the propeller would on the other hand (other factors being equal) increase the thrust, since the convergence of the tail-water is thereby counteracted. On the other hand the forward curving of the guide line towards the direction of travel, have proved to result in an increased thrust, but at the same time in an increased liability to cavitation at the boss, since the whole blade in consequence of its jet-like action counteracts the constriction of the tail-water and can generate no centripetal falling-off of the pressure in the region of the boss.

The present invention provides a special shaping of the generating lines of the blade combining the advantages of the above-described principles of design while avoiding the disadvantages of the same.

This shaping of the blades provided by the present invention may be defined as follows. The generating line of the surface of the blade is inclined or curved in the region of the transition of the blade into the boss of the propeller, this is to say for approximately the first third of the length of the blade from the boss to the tip, in the direction opposed to that of the thrust, and in the last third of this length towards the direction of the thrust. It follows that in the remaining middle third of this length the direction is mainly axial. This principle of designing the blades enables all the advantages partially and singly obtained by the above-described expedients to be attained simultaneously. The substantially

radial direction is maintained, thus taking account of the fact proved by experience that the propeller-blade the generating lines of which are of axial direction possesses the greatest strength and resistance to inherent vibration. The forwardly bent outer portion of the blade enables a comparatively greater quantity of water to be held than in the case of other forms of construction; the conical stream of water produced by the tips of blades thus formed constitutes a jacketing about the inner core of water in the manner of a solid auxiliary suction-tube. This effect in its turn results in a considerable increase in the quantity of fluid acted upon by the main middle portion of the blade and therefore also in an increase of the thrust.

Further the backwardly curved guide line in the inner third of the blade gives rise to a centripetal pressure component, thus eliminating cavitation at the boss.

An example of a screw-propeller designed in accordance with the present invention is shown in longitudinal section in the accompanying drawing. The screw-propeller, which rotates about the axis 1, is provided with blades 2 which are so shaped that the generating line 3 or the locus 4 of the centres of gravity of the cross-sections of the blade is inclined at the base of the blade in a direction away from the direction of travel 6; towards the middle of the blade at 7 the generating line gradually assumes a direction at right angles to the axis of the propeller; and in the outer third of its length the generating line gradually acquires an increasing inclination or curvature in the direction of travel, so that the tip 8 of the blade is located furthest towards the front. In this example of a form of construction shown in the drawing the line joining the base 5 of the blade with the tip 8 of the same is at right angles to the axis of the propeller, but the angle of inclination α may equally well be greater or less than 90° . The essential feature of every possible embodiment of the invention is that the angle of inclination β between the tangent to the generating line at the base 5 of the blade and the axis of rotation of the propeller on the side towards the stern is an acute angle, while the corresponding angle γ of the tangent at the tip of the blade is obtuse. The resulting shape of the generating lines is naturally with the concave side towards the front. The main direction of the mid-portion of the generating lines should be approximately at right angles to the axis of rotation of the propeller, although slight deviations are permissible, so that the tip 8 of the blade may be somewhat in front of or behind the base 5 of the blade considered in an axial direction. A design embodying a blade tip in advance of the

blade base has the advantage over other types that the bending component which results from centrifugal force in the blade and acts counter to the thrust of the propeller reduces the total strain on the material of the propeller and enables the cross-sections of the blades to be kept thinner than would otherwise be the case.

If the above described conditions be observed together with the known principles and proportions regarded as ruling in respect to diameter, pitch, profile, superficial area, number of blades, etc., in the designing of propellers the possibility is given by the present invention, by the mere determining of the course and shape of the generating lines of the blade surface, to improve any and every type of propeller both as to efficiency and load capacity. The improvements achieved in this manner are valid for the entire range of the permissible speeds.

A further consequence of the effective gains thus effected is that for a given thrust the superficial area of the blades can be reduced, which leads to a further increase in efficiency.

We claim:—

1. In a screw-propeller having a boss, concave blades as viewed from the suction side and carried by the boss, said blades being characterized by the essential feature that the generating line of the said blades is inclined in the first third of the radial length of the said blades adjacent the boss of the said propeller in a direction away from the direction of travel of the propeller, in the next following middle third of the said length in a direction coinciding with the direction of travel at right angles to the axis of rotation of the said propeller, and in the final outer third of the said length in a direction towards the direction of travel.

2. In a screw-propeller having a boss, concave blades as viewed from the suction side and carried by the boss, said blades being characterized by the essential feature that the generating line of said blade is inclined in the first third of the radial length of said blades adjacent the boss in the direction of the thrust of the propeller, in the next following middle third of said length in a direction coinciding with the normal direction of travel at right angles to the axis of rotation of the said propeller and in the final outer third of said length in a direction towards the direction of travel.

In testimony whereof we have affixed our signatures.

FRANZ MELCHER,
ERNST SCHNEIDER.
